(57) **CLAIM**

The ornamental design for a home beauty device as shown and described.

DESCRIPTION

FIG. 1 is a first perspective view of a home beauty device, according to the present invention;

FIG. 2 is a second perspective view of the home beauty device of FIG. 1;

FIG. 3 is a third perspective view of the home beauty device of FIG. 1;

FIG. 4 is a third perspective view of the home beauty device of FIG. 1;

FIG. 5 is a front elevation view of the home beauty device of FIG. 1;

FIG. 6 is a rear elevation view of the home beauty device of FIG. 1;

FIG. 7 is a first side elevation view of the home beauty device of FIG. 1;

FIG. 8 is a second side elevation view of the home beauty device of FIG. 1;

FIG. 9 is a top side elevation view of the home beauty device of FIG. 1; and,

FIG. 10 is a bottom side elevation of the home beauty device of FIG. 1.

The broken lines shown throughout the FIGURES depict unclaimed subject matter and form no part of the claimed design.

1 Claim, 9 Drawing Sheets
